Patented Aug. 20, 1918.

UNITED STATES PATENT OFFICE.

CHARLES W. MCKIBBEN, OF HOUSTON, TEXAS.

METHOD OF SEPARATING ASSOCIATED LIQUIDS.

1,276,387.

Specification of Letters Patent. Patented Aug. 20, 1918.

Application filed January 22, 1918. Serial No. 213,236.

To all whom it may concern:

Be it known that I, CHARLES W. MCKIBBEN, a citizen of the United States, residing at Houston, in the county of Harris and 5 State of Texas, have invented certain new and useful Improvements in Methods of Separating Associated Liquids, of which the following is a specification.

My invention relates to the art of separating associated liquids, in which particles of one liquid are held, or bound in mechanical suspension in another, as in emulsions. It is especially applicable for the treatment 10 of liquids differing in specific gravity and 15 specific electrical conductivity, such, for example, as crude petroleum and water.

One of the especial objects of this particular invention is to provide a method of separation of two mechanically associated liquids, such as water and oil when combined 20 in mechanical relation, as in emulsions, by application of electric current, in which the current is maintained at all times through the liquid to produce polarization and to 25 prevent entire depolarization of the molecules of the imprisoned water globules when inclosed in oil filaments, and held therein by the effect of surface tension of the enshrouding oil films.

Another object of my invention is to provide means whereby to prevent the current of electricity from increasing in value, above a predetermined degree, when the path through the liquid changes in resistance 30 by the interchange of oil and water as the process of separation progresses.

Another object of my invention is to provide a process of separation of entrapped water, from oil, which is continuous, rapid, 40 economical and efficient.

Other and further objects of my invention will become readily apparent, to persons skilled in the art, from a consideration of the following description when taken in conjunction with the drawings, wherein is shown a schematic representation of apparatus, comprising closed conduits and receptacles by which my invention may be carried into effect.

In my copending application for a method of separating associated liquids, filed December 14th, 1917, and identified by Serial No. 207,174, I have shown a similar method of procedure in which current of 50 constant potential is employed for the purpose of polarizing the globules of water and

breaking the enshrouding films that incloses the water globules. One of the objections to such a method is the extreme variation of current value due to the rapid and pronounced 60 change of electrical resistance in the path of the current, through the liquid, as the water becomes liberated and displaces the oil, or the oil emulsion. When a current of electricity, of relatively high potential is employed for this purpose, and the water in the paths or chains of globules or streams within the emulsion, substantially short circuits the source of current supply, the effect is to cause the current to rise in strength 65 or value, to such a degree as to practically decompose the water into steam and violently affect the source of current supply. In such a procedure the current rapidly varies from maximum to practically zero, due 70 to short circuiting and to substantially open circuit, through the liquid.

When the liberated water in certain strata or streams has substantially displaced the emulsified liquid, the path of the current is 80 thereby very materially decreased in resistance, substantially short-circuiting the source of current supply. When the freed water has been precipitated below the path of the current through the emulsion, or has 85 been carried by any means beyond it, and replaced by the emulsified liquid, or substantially purified oil, the path of resistance is infinitely increased, thereby reducing the current to such an extent as to almost open 90 the circuit.

The object of my present invention is to automatically control and maintain the current, at all times, in the emulsion, so that the molecules of water will never at any time 95 be entirely depolarized and so automatically control the current that its value, under no circumstance, will ever attain a predetermined dangerous degree. This procedure effects a more even and economical result 100 than can be attained by the spasmodic opening of the circuit, as there is no beneficial action during the time when the current is withdrawn, by the unlimited increase of resistance following the abnormal increase of 105 current, as heretofore stated.

The physical properties of heat cause natural repulsion of the molecules of the liquid when heated, thus diminishing the force of their cohesion, decreasing the viscosity 110 of the liquid, and increasing its mobility.

2
 The particles, or globules constituting water and oil, are each subject to this effect, by increase of temperature. When water and oil, such as petroleum, are associated as 5 an emulsion, when heated, the expansion effect tends to attenuate the walls of the enshrouding oil filaments, or that which intervenes between adjoining water globules, and to decrease their surface tension, therefore, 10 when the emulsion is preliminarily heated, it is the best or most propitious time to apply electricity to further the effect or complete the destruction of the oil envelops or films that imprison the myriads of small 15 particles of water, or to so deplete them that they can no longer hold and segregate the many particles of water against their mutual tendency to cohere, but yield to the mutual attraction thereof, which effect results in the 20 coalescing of many smaller particles into many larger globules of free water.

In the practice of my invention of separation I preferably heat the emulsion in a pressure tight receptacle, to a temperature 25 that best suits the particular emulsion, which may vary from 135 to 180 degrees Fahrenheit. The only pressure actually required is enough to urge the fluid at suitable velocity through the apparatus. The 30 pressure could be anywhere required for the purpose, say probably about 20 pounds per square inch, more or less. I then pass the emulsion through an intense electrical field, produced by a current of electricity, preferably, alternating current, under variable 35 pressure, in accordance with and as the characteristics of the emulsions vary, and, preferably, in a vertical direction, so that part of the freed water may settle, by the effect 40 of gravity, into a chamber below the body of the rapidly moving emulsion. Because of its great velocity through the treater, some of the freed water may pass through 45 to the settling tank with the oil, and there, most of the water drops out, or is precipitated, in the course of time, to the bottom of the tank.

As the emulsion passes through the treater, or the vertically disposed conduit, 50 it is subjected to the action of a strong electric field, which produces polarization of the water globules or particles, increasing their affinity for each other, and causing them to strongly approach each other by 55 mutual attraction, whereupon the oil is pressed out from between the globules, causing the inclosing walls to become thinner or more attenuate. The resistance of the normally interposed oil, being relatively larger 60 than that of the entrapped water, the electric current, which inherently will select paths of least resistance, will flow through these globules of water formed into chains or streams by polarizing effect, where the intervening walls of the oil are thinner, thus 65

intensifying the polarization of the particles along the aforesaid paths which further reduces the resistance, by further attenuating the walls, through the tendency of the particles or globules to cohere or reunite into 70 drops or larger bodies or continuing streams of water, until the vigorous upward movement of the liquid, and said coöperating electrical effect, causes rupture of the inclosing oil filaments surrounding the small particles of water, liberating them, whereupon their mutual attraction causes the freed drops to cohere into relatively large conglomerate globules or bodies and some of the water, thus freed, gravitates to the bottom 80 of the upwardly moving body of emulsion, out of its path, and into the settling chamber therebelow, but some of the freed water, on account of its high velocity, and the high velocity of the moving liquid, is carried over 85 into the settling tank.

Notwithstanding the high velocity of the liquid moving through the separator, the nascent streams of water resulting from the aligned conglomerate globules span the electrodes of the treater and provide such a low resistance path for the current of electricity as to amount, substantially, to a short circuit, whereupon the current from a constant potential source, would rise to such huge 95 proportions as to be practically impossible without periodically opening the circuit. In my present invention I provide means for controlling the current so as to prevent abnormal rise of current, and the consequent 100 opening of the circuit, as a result thereof, to protect the instrumentality, such as the dynamo or the like, for producing the current by which the current is maintained constantly in the liquid and prevented from increasing in value beyond a predetermined extent.

By using an ordinary transformer to step the current up from a source of constant potential, of a lower electro-motive-force, a 110 reactance coil, of proper dimensions, may be placed in the secondary circuit, which has the effect of preventing the current, in that circuit, from rising above a certain predetermined value proportional to the reactance capacity of the coil. The reactance in the secondary circuit does not oppose the current but tends to cause a displacement of the phase between that of the current and the electro-motive-force. The reaction, 120 therefore, increases or tends to increase, as the current tends to increase, and hence the value of the current is maintained at, or prevented from rising to, an objectionable and dangerous extent. The effect of this 125 arrangement is such that any tendency for the current to rise, above a predetermined value, automatically displaces the phase of the electro-motive-force and current to such a degree as to decrease the effective electro- 130

motive-force and consequently prevents abnormal increase of current. This effect takes place, automatically, without the necessity of suspending the current or opening the circuit, and therefore the particles or molecules of water, to be affected by the current in the manner heretofore described, are always polarized and never released or liberated from their mutual polar-relation.

10 In my earlier application I have disclosed a method of procedure similar to that included in the present application with the exception that the current applied to the liquid, for the purpose of separating the water from the oil, is of constant potential character and when the resistance through the liquid becomes depreciated to such an extent as to cause substantial short circuit, a current controlling device must be provided

15 to open the circuit, as a precautionary measure, to prevent explosion, or injury to the source of electric current, thereby suspending the operation of the current for a brief period of time and permitting certain qualities of the emulsion to pass through the treater without having the constituent liquids separated. In this present invention the current is always present and, therefore, all of the emulsion that passes through the

20 treater is acted upon in the same manner, and to the same extent.

25 In the present invention I provide electrodes in the settling chamber and an electro-responsive device for opening the discharge valve from the settling chamber upon increase of the water content and for closing it after the water has been expelled from the settling chamber and replaced by the liquid of higher resistance, such as an

30 emulsion, or oil.

35 In the accompanying drawing I have shown, in Figure 1, a schematic relation of a series of tanks, conduits, electric circuits, etc., for carrying my invention into effect.

40 Fig. 2 shows another form of current regulator.

45 5 is a pressure-tight storage tank for containing emulsion to be treated, which is pumped into the tank through a pipe 6, having a downturned end 7, just above a steam heating coil 8, in which the steam may be superheated. A discharge pipe 9, is provided with an upwardly extending part 10, and a laterally extending end 11 having a gas trap cup 12 over the upper end 13 to prevent the gases, that may be contained in the upper part of the tank from escaping through the discharge pipe 9. The pipe 9 may also have an open end 14 for discharging the emulsion from the body part thereof. Freed, or entrained water will settle in the bottom part 15 of the tank and be automatically discharged therefrom. The pipe 9 has a free opening into a vertically-disposed

50 conduit or pipe 16 of the treater. The upper part of the pipe 16 is surrounded by a relatively large casing 17. An electric conductor, comprising a metallic rod 18, is supported in the center of the conduit 15 by an insulating support 19 that is fixed to the top 70 20 of the treater. The oil, coming from the pipe 9, will flow upwardly at a relatively high velocity in the conduit 16, of the treater, between the same and the electric 75 conductor 18 and overflow at the top 21 into the casing 17. A discharge opening 22 is provided above the bottom of the casing 17 and contains a goose neck trap 23. The pipe 24 conducts the relatively pure oil from the 80 treater into a closed oil storage tank 25. A heating coil 26, preferably, for super-heated steam, is contained also in the oil storage tank 25, and the incoming oil from the treater 17 passes through the pipe 27 immediately above the heating coil. The object of putting the heating coil 26 in the oil tank 25 is to maintain the oil at a relatively 85 high temperature to encourage the further separation of any entrapped, or free water, 90 that may be carried over through the treater into the oil storage tank, by the coalescence of the globules and precipitation to the bottom of the tank.

95 The emulsion treater 17 is fully described and claimed in an application Serial No. 203,695 filed by me on the 24th day of November, 1917. Briefly it consists of the parts described, with a settling chamber 30 below the bottom of the inlet to the vertical pipe 16 and a discharge pipe 31 leading therefrom, controlled by a valve, operated by an electro-magnet 32. A relay 33 is in circuit with a secondary coil 34 of the transformer which is in inductive relation with 100 the primary coil 35 thereof and which, through an adjustable resistance 36, is in circuit with the relay coil 37, and with a centrally disposed conductor 38 that projects into the settling chamber 30. The electro-magnet 32, controlling the valve in the discharge pipe 31, is energized by a source of current which may be a battery 39, or other 105 source.

110 The centrally disposed conductor 18 of the treater, in the conduit 16, is connected by a wire 40 to the secondary coil 41 of the transformer including a reactance coil 142 in series with the secondary coil and provided with a magnetic core 143, which is adapted 115 to be moved into and out of the reactant coils 142, to increase and decrease the reactance effect of the coil. The secondary circuit is grounded, as at 43, and the pipe 9 is grounded, as at 44. The secondary coil 34 120 of the transformer 35 is grounded, as at 45.

125 In Fig. 2 I have shown another constant current transformer of a well known type, possessing a rather higher power factor and therefore more efficient. In either case,

counter-electro-motive force, or its equivalent, is automatically interposed in the working circuit to prevent abnormal rise of current when the resistance of the working circuit is suddenly reduced, to a greater or less degree, by the formation—or tendency to form—of chains of globules or streams of water between the electrodes in the treater.

A constant direct current could be used 10 with a suitable current regulator, but I prefer to use alternating current and thus avoid objections due to electrolysis and gradual disintegration of the electrodes.

In the operation of the apparatus the oil 15 will pass from the pressure tank 5, heated as heretofore described and under pressure and through the pipe 9 into the conduit 16 of the treater between the inner wall of the conduit and the centrally disposed, vertically 20 extending conductor 18, through an intense electrical field produced by an alternating current dynamo 145. The voltage applied to the electrical field in this particular case, will depend upon the changing resistance or 25 the interposed liquid electrical conductor. The more water that is interposed between the conductors and the treater, the less will the electro-motive-force be, it being reduced by the displacement of the phase of electro- 30 motive-force and current, as heretofore explained, as a result of the included reactance in the secondary circuit, and therefore the current will always pass between the central conductor and the inside walls of the conduit 35 16 and produce the electric field in a manner clearly understood by persons skilled in the art.

In carrying out my invention, the emulsion passes upwardly through the pipe 16 40 and overflows at the end 21 of the pipe, at a high velocity, and as the space between the interior surface of the conduit and the central conductor, is relatively small, with an attendant low resistance, the electro-motive 45 force may be relatively large, and as a result, the liquid, moving at a relatively high velocity, a very heavy current is permissible with relatively low voltage, because the upward movement of the emulsion, through the conduit, will tend to break up the streams or 50 chains of water globules that will be formed by the polarizing effect of the current. The electric field causes, or tends to cause constant formation of series of chains of polarized water globules or streams of water between the electrodes during the upward movement of the emulsion and these polarized conglomerate globules are rapidly being broken asunder, or disrupted, by the 55 energetic movement of the liquid through the conduit and the tenacious persistence of the polarizing effect, while they are under treatment. At the same time, other globules, coming into the field are being polarized 60 and being broken up in the same manner and

this operation is going on continuously, because, not for one second, is the current suspended, to permit untreated emulsion to pass through the conduit without application of the influence of the electric current. As the 70 myriads of particles of water are liberated, they coalesce into larger globules, or streams of water, and are, as a result of their higher specific gravity, precipitated to the bottom of the tube 16 and into the settling chamber 75 therebelow. Some of the freed water may be carried over at the top of the conduit, into the chamber 17 and some of it may be carried through the pipe 24 into the settling tank 25, but being freed and present, in relatively 80 large bodies, and no longer comminuted and inclosed by the films of oil, it will be precipitated to the bottom of the settling tank 25, there to be automatically 85 expelled by the apparatus shown at the bottom of the tank and which has been heretofore specifically described.

As the various particles of water are liberated, in the manner heretofore described, they coalesce into larger globules or bodies 90 and as such they possess a higher specific electrical conductivity than the emulsion of which they were a part, or than the purified oil. The water that is contained at the bottom of the receptacle shown in the drawings, as for instance, in the settling chamber 30, intervenes between the electrode 38 and the inner walls of the chamber. This resistance is sufficiently low, by the displacement 95 of the oil, due to the accumulation of the heavier water therein, the current will then be strong enough in the relay 37, to close the local circuit, to operate the valve-moving magnet 32, thereby automatically opening the valve of the discharge pipe 31 and permitting the water to flow from the settling chamber 30. As the emulsion passes into the settling chamber 30, following the discharge of the water, the electrical resistance 100 between the central conductor 38 and the inner surface of the walls of the settling chamber, will be greatly increased, reducing the strength of the current through the relay 33, causing retraction of its tongue, which will open the local circuit and cause the 105 closing of the valve that governs the discharge pipe 31. By this means the water, freed from the emulsion, is automatically discharged. A similar device may be placed, as shown, at the bottom of the tanks 5 and 110 25, so as to dispose of the accumulation of water that may settle in the bottom of these receptacles. This particular feature is more completely disclosed in my copending application, to which reference has heretofore 115 been made.

Emulsions containing petroleum oil have their own individuality, or characteristics, manifested in variations of viscosity, surface tension, specific gravity, tendency of cohe- 120 130

sion, boiling point and electrical conductivity. Some of these effects may be due to the variation in the quality and quantity of the salts contained in the entrapped wa-
5 ter and some to other causes.

To provide for adjustment that may be required as a result of these differences, the conductor 18, in the center of the tube or conduit 16, may be adjustably raised or low-
10 ered to vary the surfaces of the confronting electrodes requisite for the variation of the oil characteristics. By this means the de-
vice is made adjustable so as to handle emul-
15 sions that come from the tanks, or tank farms or oil direct from the wells, or from the refineries or other oils that may now be otherwise thrown away.

To prevent the gases or vapors that may be contained in the upper part of the various containers from escaping, I condense them by providing a condenser 53 and connect it by pipes 55 to the upper ends of the tank 5 and the treater 17, and by the pipe 51 to the tank 25. The discharge end of the con-
25 denser is connected to the pipes 11 for the condensed vapor and purified oil. The in-
terior cooling element within the casing 55, comprising the headers 56 and 57 and the connecting pipes 58, is to contain water, at
30 a relatively low temperature, carried thereto and taken therefrom by pipes 59 and 60. The oil in the receptacle being hot, it more freely vaporizes and this is an economical means for reclaiming it. By using an ab-
35 solutely closed system for the treatment of the emulsion, there is no escaping gases that would increase the fire or explosion hazards, or other destructive effects, that may arise therefrom, and the system is efficiently en-
40 hanced by being able to condense these gases into purified oil.

In practice, oil coming from the treater into the settling tank 25, is between 135 and 180 degrees F., and the gases distributed at
45 these temperatures readily condense and pass out through the pipe 11 as commer-
cial oil.

While I have herein shown an apparatus

by which my invention may be carried into effect, it is manifest to persons skilled in the art that I am not limited to the peculiar apparatus and devices shown for the purpose, as my invention consists in the process or steps in the process, for accomplishing the result described.

Having described my invention, what I claim is:—

1. Improvements in the art of separating liquids, in which small particles of one liquid are mechanically suspended in another, 60 which consists in heating the associated liquids to a temperature below the boiling point of the mixture; passing the liquid through a path between suitably electrically-energized electrodes, at a velocity sufficient 65 to prevent the persistance of chains of polarized globules of the entrapped liquid after they have been formed into nascent streams between the electrodes and automatically reducing the effective electro-motive-force of 70 the applied current when the streams begin to form.

2. Improvements in the art of separating liquids, in which small particles of one liquid are mechanically suspended in another, 75 which consists in heating the associated liquids to a temperature below the boiling point of the mixture; passing the mixture through a path between suitably electrically-energized electrodes, at a velocity sufficient 80 to prevent the persistance of chains of polarized globules of the entrapped liquid after they have been formed into nascent streams between the electrodes; automatically reducing the electro-motive-force of the ap- 85 plied current, when the streams begin to form to prevent abnormal rise of current and to maintain the current uninterruptedly through the mixture.

In testimony whereof I hereunto set my hand in the presence of two subscribing wit-
nesses.

CHARLES W. McKIBBEN.

In the presence of—

W. W. BALES,
A. B. MAERCKY.
